UNITED STATES PATENT OFFICE.

WARD MELVILLE, OF NEW YORK, N. Y., ASSIGNOR TO THE MELVILLE SHOE CORPORATION, OF NEW YORK, N. Y., A CORPORATION OF NEW YORK.

DESIGN FOR A SHOE-HEEL.

55,393.

Specification for Design.

Patented June 1, 1920.

Application filed January 14, 1920. Serial No. 351,490. Term of patent 14 years.

To all whom it may concern:

Be it known that I, WARD MELVILLE, a citizen of the United States, residing at 121 Duane street, in the city of New York and State of New York, have invented a new, original, and ornamental Design for a Shoe-Heel, of which the following is a specification, reference being had to the accompanying drawing, forming a part thereof.

The figure is a bottom plan view of the shoe heel, showing my new design.

I claim:

The ornamental design for a shoe heel, as shown.

WARD MELVILLE.
